RAILWAY SIGNALING SYSTEM

William W. Hartzell, Melrose, Mass., assignor to
 General Railway Signal Company, Rochester,
 N. Y.

Application May 8, 1941, Serial No. 392,465

5 Claims. (Cl. 246—52)

This invention relates in general to a wayside signaling system for railways, and has more particular reference to means for providing added safeguards against accident and simplified means for carrying such safeguards into effect.

One of the objects of the present invention is to provide means of a simple nature cooperating with a two-arm wayside signal which is effective to shift the then control of the upper arm, to the lower arm, while disconnecting the control of the lower arm, in the event of failure of the upper arm.

Another object of this invention is to provide means for placing the lower arm signal at danger if the control means for the upper arm should become inoperative.

Further objects, purposes and characteristic features of this invention will appear as the description progresses, reference being made to the accompanying drawing, showing in a wholly diagrammatic manner, and in no way whatsoever in a limiting sense one form which the invention can assume. In the drawing—

Fig. 1 is a wholly schematic representation of one form of the present invention.

Fig. 2 is a table showing the various signal aspects obtained under various conditions.

Referring now to the drawing, and first to Fig. 1, there is here represented a stretch of single track divided into isolated signal sections 3, 5, 7, 9 and 11 by usual insulating joints 12 with section 11 entering an interlocking plant, or including a turnout, such as 13, whereby this signal section is an approach to an added traffic hazard. The signal sections are supplied with track batteries and track relays in the usual manner, although, except in special instances, as will appear below, these devices have not been shown on the drawing in the interest of clarity.

At the entrance to each signal section is a wayside signal such as the signal 5G, having an upper arm A and a lower arm B. These separate arm signals are represented as being color light signals of the type known as the SA signal, such, for instance as shown in the O. S. Field patent, No. 2,097,785, granted November 2, 1937. Each signal of this type has a single light source with a spectacle movable in front of the light source having different colored roundels, as red, yellow and green, with a mechanism for moving the spectacle relatively to the light source. If the signal mechanism be energized with current of one polarity, which may be termed normal polarity, the signal aspect is green, if energized with current of the other polarity, which can be

termed reverse polarity, the signal aspect is yellow, while if the mechanism be deenergized the signal aspect is red. The signals at the entrances to the other sections shown have not been represented in the drawing, in the interest of simplicity, but can be of the same general type as that represented at the entrance to section 5, although some of the signals may include a different number of arms, as three, for example.

The direction of traffic in this system is considered to be easterly as indicated by arrow 14.

The signal 5G is shown somewhat in detail in the circuit diagram of this figure. It comprises a light source 15, and an operating mechanism 5GA for the upper arm, and a light source 16 and an operating mechanism 5GB for the lower arm. In series with the two light sources are adjustable current limiting means 17 and 18.

The energy for the light sources is normally 20 from an alternating current source having terminals BX and CX, but a reserve source of direct current is available having terminals B and C. Connected in series with the alternating current source is a power-off relay POR which is energized so long as the alternating current source is available but in the event that this source fails relay POR releases to cause its contact fingers 19 and 20 to shift from their front points as shown, to their back points whereby to cut in the direct current source. The alternating current source includes a transformer TR, the secondary of which is connected to the front points of contact fingers 19 and 20 of the power-off relay.

Involved in the system is a light-out relay LOR 35 which can be of any suitable type, as, for example, a usual tractive type direct current relay. It has an upper winding UW and a lower winding LW positioned on a common core, and a rectifier Rec. connected across the lower winding.

The upper winding of light-out relay LOR is energized when there is no occupancy of track section 3 by a circuit including contact finger 21 and front point of an approach energy relay AER which in turn is energized through a circuit including the contact finger 3T and front point of the track relay for section 3.

The light-out relay has an energizing circuit for its lower winding LW which is normally open but which becomes closed upon release of the approach energy relay AER. This circuit includes one side of the secondary of transformer TR, wire 22, contact finger 19 and front point of relay POR, wire 23, contact finger 24 and back point of relay AER, wires 25 and 26, winding LW, wire 27, upper signal arm light source 15, cur-

rent limiting means 17, wire 29, contact finger 20 and front point of relay POR, and wire 30 to the other side of the secondary of transformer TR. Thus it can be seen that the lower winding of relay LOR is in series with the light source of the upper arm of signal 5G and thus this winding becomes deenergized if the signal filament fails for any reason whatsoever.

The light source of the lower arm of signal 5G has an energizing circuit which includes the 10 secondary of transformer TR, etc., as in the circuit traced just above, up to the wire 25, and thence through a branch circuit including wire 31, lamp 16, and current limiting means 18, to wires 28 and 29 of the circuit traced just above.

Thus, when the approach energy relay has released, the signal light sources and the lower winding of relay LOR are all normally energized by alternating current. Should the source of alternating current fail for any reason, power-off relay POR releases whereby the direct current source of energy is substituted for the alternating current source, and the signal light sources and the lower winding of relay LOR are then energized with direct current.

It should be noted that rectifier Rec. is poled as to oppose the flow of this direct current through it, whereby to prevent shunting the direct current away from lower winding LW. When the lower winding LW is energized by alternating current, however, only one-half of each cycle of alternating current is shunted out by the rectifier, the other half being blocked and thus passing through the relay lower winding so that the lower winding is energized by pulsating direct current so as to hold up tightly on alternating current and prevent any failure of operation or chattering.

Upon light-out relay LOR having its upper winding deenergized, the decay of flux in the common core induces a voltage which sends a current through the lower winding in a direction to readily pass through the rectifier, whereby to make the relay slow to release. Relay LOR need not include any short-circuited copper band, or the like, to make it slow to release since the rectifier not only serves to permit the relay to hold up readily and certainly on alternating current but also imparts necessary slow release characteristics necessary in the relay for reasons 50 to appear below.

The upper arm signal mechanism 5GA is energized from a direct current source through a circuit including contact finger 33 and front point of a relay 7GBGP, contact finger 5T and front point, contact finger 34 and front point of relay LOR, the mechanism 5GA and contact finger 35 and front point of relay 7GBGP. These contact fingers 33 and 35 constitute a part of a pole changer whereby to energize the signal mechanism with current of either normal or reverse polarity, dependent upon whether the controlling relay be energized or deenergized. This relay 7GBGP is a relay which repeats the green indication of the signal 7G at the entrance to section 7. Thus, this relay is deenergized when the lower arm of signal 7G is giving either a red or a yellow indication, and is energized when this signal arm is giving a green indication.

The signal mechanism 5GB of the lower arm of signal 5G is energized from a source of direct current through a circuit including contact finger 36 and front point of a relay 7GAYGP, contact finger 37 and front point of a relay 75

5GAYGP, contact finger 38 and front point of relay LOR, the mechanism 5GB, contact finger 39 and front point of relay LOR, and wire 40. The relay 7GAYGP is a relay which repeats the yellow and the green indications of the top arm of the signal 7G and thus it is energized when the upper arm of signal 7G is indicating either yellow or green, but is deenergized when this signal indicates red.

In like manner, relay 5GAYGP is a repeater of the yellow-green aspects of the upper arm of signal 5G and is energized when the upper arm of signal 5G displays yellow or green and is deenergized when it displays red. These signal repeater relays are well known in the art, as is shown, for example, in the patent to S. M. Day, No. 2,105,905, granted January 18, 1938.

If, for any reason, as perhaps, because of failure of the filament of lamp 15 of the upper arm of the signal 5G, relay LOR releases, its contact fingers 38 and 39 will leave their front points, and thus cut the lower arm signal mechanism off from its control circuit as described above, and by making up their back points will connect it through wires 41 and 42 to the control circuit for the upper arm mechanism by reason of contact finger 34 leaving its front point and making up its back point. The movement of contact finger 34 from its front point, of course, causes deenergization of the signal mechanism of the upper arm of the signal whereby to cause its spectacle to move to its red position. Since, however, the light source has failed, the signal will be a dark signal.

Assume now that a train, moving in an easterly direction enters section 3. Signal 5G has both arms positioned for displaying a green indication, or green over green, that is, G/G.

Release, however, of the track relay for this section 3 opens the energizing circuit for relay AER at contact finger 3T and front point, whereby contact fingers 21 and 24 of the approach energy relay release. The release of contact finger 21 deenergizes the light-out relay LOR but since this relay is slow to release due to the rectifier bridged across it, before it releases the making up of contact finger 24 with its back point, energizes the lower winding LW of this relay in series with the light source 15 so that relay LOR normally does not release. Also in multiple with the light-out relay and the light source 15, the light source 16 for the lower arm of signal 5G is energized. Should the alternating current source fail for any reason, power-off relay POR will shift the circuits involved to the reverse direct current source of energy.

As the train occupying track section 3 advances through the various sections 5, 7, 9 and 11, signal 5G displays various indications as set forth in Fig. 2.

As shown in Fig. 2, with section 5 occupied, the signal 5G displays an R/R indication, since the release of the track relay for this section deenergizes the upper arm mechanism at contact finger 5T and front point and with the upper arm displaying an R indication, the repeater relay of this mechanism 5GAYGP releases to thus deenergize the lower arm mechanism.

Upon the train occupying section 7 and vacating section 5, signal 7G displays an R/R indication. As a result, signal 5G displays a Y/R indication since the release of relay 7GBGP in the control circuit for the upper arm of signal 5G puts reverse polarity on the mechanism to give a Y indication while the release of the repeater

relay for the upper arm of signal 7G, that is, relay 7GAYGP deenergizes the lower arm mechanism of signal 5G to produce an R indication.

In the same way, on the train vacating section 7 and occupying section 9, signal 5G gives a Y/G indication. Upon the train vacating section 9 and occupying section 11 signal 5G gives a G/G indication.

It can be realized that, should the filament of the upper arm of signal 5G, for example, fail, a dark signal results. If this failure should occur when signal 5G is displaying its Y/G indication, the resulting signal would appear as a G indication, and this indication, more permissive than should be in force, will give insufficient 15 braking distance for trains approaching signal 5G, with resulting possible danger. However, with the system as described above, upon the filament 15 failing, since the upper winding of the light-out relay LOR is deenergized, due to section 3 being occupied, and the relay depending for its energization upon its lower winding LW, which is in series with the light filament which has failed, the light-out relay releases. This shifts the control then existing for the upper arm of the signal, to the lower arm of the signal, and thus the lower arm of the signal changes from a G to a Y indication, while the upper arm is dark. As indicated in Fig. 2, this intended signal Y/G instead of becoming the more permissive signal aspect G, displays the aspect of a dark signal over a Y indication to constitute a more restrictive signal than the one that should have been in force.

Assume again that section 11 is occupied whereby the signal 5G is displaying an aspect of G/G and a train approaching this signal enters track section 3. Further, assume that the control circuit for the upper arm of signal 5G fails to be effective for any reason, such, for example, as a broken wire or a failure of the source of energy, or the like. Upon such a failure, the upper arm of signal 5G displays an R indication and the repeater relay 5GAYGP of this arm which has its contact 37 in the control circuit of the lower arm of this same signal, releases to deenergize the lower arm mechanism and cause it to display an R indication.

Thus, with the control circuit for the lower arm of the signal constituted as described above, such a failure as just referred to changes a signal aspect of G/G to a signal aspect of R/R which is a recognizable signal. If it were not for the provision of the repeater relay contact 37 in the lower arm control circuit, the upper arm would display an R indication while the lower arm would continue to display its G indication to give an unorthodox and confusing and possibly dangerous signal aspect of R/G.

It should further be noted that, by employing the contact 37 of the repeater relay 5GAYGP in the lower arm mechanism control circuit, an added contact on the track relay 5T is eliminated, and is replaced by a contact already available in the upper arm signal.

It is thus apparent that the various functions of safeguarding the wayside signaling system, as described above, against dangerous conditions arising, due to failure of lamp filaments and of mechanism control circuits, are accomplished in a very simple and economical manner. This is realized by employing a single double-wound relay LOR for the light-out function, and by employing a rectifier in connection with this relay, which not only imparts slow release characteristics to the

relay as a whole, but fits the lower winding of the relay to be efficiently and dependably energizable by either alternating or direct current.

The above rather specific description of one form which this invention can assume is given solely by way of example, and is not intended in any manner whatsoever in a limiting sense. It is to be understood that various modifications, adaptations and alterations may be applied to meet the requirements of practice without in any manner departing from the spirit and scope of the invention, except insofar as limited by the appended claims.

Having described my invention, I now claim:

1. In a railway signal system, in combination, a signal comprising an upper and a lower arm, each of which includes a light source, an operating mechanism, a control circuit for the light source, and a control circuit for the mechanism, means controlling each mechanism control circuit in accordance with traffic conditions, a light-out relay having two windings, an energizing circuit for one of the windings, an energizing circuit for the other winding including one of the light sources in series, means controlled by approaching traffic for deenergizing said one winding and energizing said other winding and the light sources, and means effective, upon failure of said one light source, to shift the control 20 of the mechanism of said one light source to the other mechanism, and to disconnect said other mechanism from its own control circuit.

2. In a railway signal system, in combination, a signal comprising an upper and a lower arm, each of which includes a light source, an operating mechanism, a control circuit for the light source, and a control circuit for the mechanism, means controlling each mechanism control circuit in accordance with traffic conditions, a light-out relay having two windings, an energizing circuit for one of the windings, an energizing circuit for the other winding including one of the light sources in series, means controlled by approaching traffic for deenergizing said one winding and energizing said other winding and the light sources, means effective upon failure of said one light source to shift the control of the mechanism of said one light source to the other mechanism and to disconnect said other mechanism from its own control circuit.

3. In a railway signal system, in combination, a signal comprising an upper and a lower arm, each of which includes a light source, an operating mechanism, a control circuit for the light source, and a control circuit for the mechanism, means controlling each mechanism control circuit in accordance with traffic conditions, a light-out relay having two windings, an energizing circuit for one of the windings, an energizing circuit for the other winding including one of the light sources in series, means controlled by approaching traffic for deenergizing said one winding and energizing said other winding and the light sources, means effective upon failure of said one light source to shift the control of the mechanism of said one light source to the other mechanism and to disconnect said other mechanism from its own control circuit, a rectifier bridged across said other winding, a source of alternating current in the energizing circuit for the other winding, a stand-by source of direct current, and means to replace the alternating

ing current source by the direct current source upon failure of the alternating current source.

4. In a railway signal system, in combination a signal comprising an upper and a lower arm, each of which includes a light source, an operating mechanism, a control circuit for the light source, and a control circuit for the mechanism, means controlling each mechanism control circuit in accordance with traffic conditions, a light-out relay having two windings, an energizing circuit for one of the windings, an energizing circuit for the other winding including one of the light sources in series, means controlled by approaching traffic for deenergizing said one winding and energizing said other winding and the light sources, means effective, upon failure of said one light source, to shift the control of the mechanism of said one light source to the other mechanism and to disconnect said other mechanism from its own control circuit, a rectifier bridged across said other winding, a source of alternating current in the energizing circuit for the other winding, a stand-by source of direct current, and means to replace the alternating current source by the direct current source upon failure of the alternating current source, the rectifier being poled to block flow of direct current from said replacement source.

5. In a railway signal system, in combination,

a signal comprising an upper and a lower arm, each of which includes a light source, an operating mechanism, a control circuit for the light source, and a control circuit for the mechanism, means controlling each mechanism control circuit in accordance with traffic conditions, a light-out relay having two windings, an energizing circuit for one of the windings, an energizing circuit for the other winding including one of the light sources in series, means controlled by approaching traffic for successively deenergizing said one winding and energizing said other winding and the light sources, means effective, upon failure of said one light source, to shift the control of the mechanism of said one light source to the other mechanism and to disconnect said other mechanism from its own control circuit, a rectifier bridged across said other winding, a source of alternating current in the energizing circuit for the other winding, a stand-by source of direct current, and means to replace the alternating current source by the direct current source upon failure of the alternating current source, the rectifier being poled to block flow of direct current from said replacement source and to make the relay slow to release upon deenergization of said one winding.

WILLIAM W. HARTZELL.
